UNITED STATES PATENT OFFICE.

JOHN WARREN DUTTON, OF DUTTONS LANDING, CALIFORNIA.

DITCHING-MACHINE.

SPECIFICATION forming part of Letters Patent No. 776,124, dated November 29, 1904.

Application filed June 3, 1904. Serial No. 211,020. (No model.)

To all whom it may concern:

Be it known that I, JOHN WARREN DUTTON, a citizen of the United States of America, residing at Duttons Landing, county of Solano, and State of California, have invented certain new and useful Improvements in Ditching-Machines; and I hereby declare the following to be a full, clear, and exact description of the same, reference being had to the accompanying drawings, forming a part of this specification.

This invention relates to certain improvements in apparatus for ditching and excavating land for drainage or irrigating purposes, and is an improvement on apparatus for excavating described in Letters Patent of the United States, No. 716,246, granted to Albert Klatt December 16, 1902, for improvements in excavating-machines, of which Letters Patent I am sole owner.

My improvements consist in an improved form of the excavating-buckets and in the means of operating the same, as described in the following specification and illustrated by drawings that accompany and form a part of the same.

The object of my invention is to attain greater celerity in working and a more perfect action of such apparatus, also the avoidance of angular corners in the bucket and an increased endurance of the various operating parts.

To these ends I construct excavating apparatus as shown in the drawings, Figure I being a side elevation of one of my improved excavating-machines; Fig. II, an enlarged vertical section through the excavating-bucket; Fig. III, an enlarged front view of the same; Fig. IV, a plan view thereof. Fig. V is a sectional view of the bucket when partially filled and closed.

In the construction of small excavating-machines for cutting ditches and like purposes the buckets are commonly single acting, having but one movable side, the other or fixed side acting as a cutting implement to sever the spoil to be removed, and as the fixed side and one or both ends of the bucket have to cut through the material to be dislodged and raised it is essential that all the fixed and op-

erating parts, including the pivoted cutting member, be kept within the bucket's contour.

Referring to the drawings, 1 is a pontoon on which superstructure is supported when employed for subaqueous working. 2 is a gallows-frame from which extends a strong connection 3, (shown broken in the drawings,) that supports the derrick 4, by which the bucket 5 is suspended, raised, lowered, and moved laterally for the purpose of discharging its load. The bucket 5 is provided with the usual guiding-spars 7, that pass through rings 8 on the derrick 4 and is closed and raised by a rope or chain 9, that passes around the pulleys 10 and 12 and is wound on a drum 13, driven by any suitable motive power, such as a gas or steam engine.

The bucket 5, which constitutes an important part of my invention, is formed of a single plate of metal bent into semicircular form at the back 14, and with integral lugs 15, to which is fastened the guiding-spars 7. This bucket 5 is open on the inner side and at the bottom, as seen in Fig. II, and adapted to be closed by the curved scoop 17, supported by the bar 18, pivoted to the sides of the bucket 19 and curved on its anterior end or edge, so as to easily penetrate beneath the material to be raised and to fit into the curved back of the bucket 5, as shown in Fig. IV. The relative positions of this curved scoop are shown in Figs. II and V. In the latter figure it is closed and partially filled with spoil.

The derrick 4 is pivotally mounted in a socket or step 20 and swings right or left in the usual manner to deposit the spoil from the bucket 5 on either bank of the ditch 21. When required, swinging shackle-pulleys 23 are provided for deflecting either or both of the ropes 9 and 22 in the usual manner. The pulley or pulleys 23 are mounted on a frame 24, that forms also a cross-support for the gallows-frame 2.

In operating the bucket 5 is suspended at some distance above the surface 25 by means of the rope 22, attached to shackle 26 on the back of the scoop 17 and winding on the drum 13. This rope sustains the weight of the bucket and at the same time holds the scoop

in the position shown in Fig. II. The bucket 5 is then dropped suddenly, severing a section 27 of spoil; but to guard against movement of the scoop 17 when the bucket 5 is descending I provide a swinging latch or detent 28, pivoted at 29 and engaging the rib 30 on the back of the scoop 17 by a notch 32, thus locking the scoop 5 in its open position, as before explained. This swinging latch or detent 28 is disengaged by a pivoted tripping-bar 33, to which is attached a cord 34, that passes over the pulleys at 35 and 37 and is attached to a weight 38, that slides loosely on the vertical guiding-bar 39. When the bucket 5 is dropped, the weight 38 slides upward on the bar 39; but the resistance thus offered is not enough to move the trip 33 and disengage the latch 28. During the ascent of the weight 38 it, however, by its momentum overruns the distance moved by the bucket 5, and then by its recoil in falling back gives a sudden jerk on the cord 34 and releases the latch 28, thus acting automatically. The bucket being then filled the rope or chain 9 is wound on the drum 13 and closes the scoop in the following manner: This rope 9 is attached at 42 to a curved lever extension 40, fastened to and projecting from the rear of the scoop 17. This curved extension 40, moved by the rope or chain 9, causes the scoop 17 to close forcibly and holds it in that position by reason of its relation to the pivotal center at 19 and also by reason of the deflecting-pulley 10. A direct vertical draft by the rope, it is found, will not hold the scoop 17 securely closed, and the angle produced by the pulley 10 is essential to safe working. After closing the scoop 17 motion of the rope or chain 9 is continued and assumes the whole weight of the bucket and its load, which are then raised and swung on the derrick 4 until over the place of deposit. Then the weight of the bucket is transferred to the rope 22 by winding the latter on the drum 13, the scoop 17 is opened by action of the rope 22 to the position shown in Fig. II, the spoil is discharged, and, the apparatus is again in position for another operation, as has been described.

In this construction it may be seen that the guiding-spars 7 being bolted within the bucket's contour and the path of the curved extension 40 being also within the bucket, nothing on the exterior of the latter offers obstruction to its descent through the spoil, and complete sections 27 can be cut out and raised whether from the surface 25 or a lower level.

Having thus explained the nature and objects of my invention, what I claim as new, and desire to secure by Letters Patent, is—

1. In ditching apparatus, a pontoon or other support, a gallows-frame and pivotally-mounted derrick thereon, an open-sided dredging-bucket suspended on the derrick, a scoop to open and close the bottom and open side of

the bucket, means to open, close, lower and raise the same, and a latch to automatically lock and release the scoop in its open position, substantially as specified.

2. In ditching apparatus, a gallows-frame, 70 swinging derrick and dredging-bucket suspended thereby, the bucket integrally formed of a single plate with an open side and bottom and upwardly-projecting lugs also integrally formed therewith and guiding-spars attached 75 thereto inside the bucket's contour, in the manner substantially as specified.

3. In ditching apparatus, an excavating-bucket open at one side and at the bottom, an oscillating scoop formed of a bent plate centrally pivoted to close the open side when open, and to close the open side and body when closed, separate means for opening and closing the same respectively, and locking means for holding the scoop in its open position until released, substantially as specified. 85

4. In ditching apparatus, an excavating-bucket with an open side and bottom, guiding-spars to hold the bucket in a vertical position attached to lugs formed integrally with 90 the ends of the bucket and within its contour, in the manner substantially as specified.

5. In ditching apparatus, an excavating-bucket open at the side and bottom, an oscillating scoop to open and close the side and 95 bottom of the bucket, a rope or chain to operate the scoop and close the bucket, and a deflecting-pulley 10 to produce draft on the bucket oblique to its upward movement, substantially as specified. 100

6. In ditching apparatus, an excavating-bucket having an open side and bottom, a pivoted scoop of curved form to close the side and bottom of the bucket, a rope or chain to close the scoop and raise the bucket, a rope 105 to open the scoop, a latch or detent to automatically engage the scoop and hold it open, and trip devices operated by a recoiling weight to automatically operate the trip and release the latch or detent, in the manner substantially as specified. 110

7. In ditching apparatus, an excavating-bucket formed from a single plate bent to a curved form to form an approximately cylindrical back and sides, leaving an open side and bottom, a pivoted scoop to close said open side and bottom, curved on its anterior edge to fit the curved contour of the fixed back and sides, means for opening said scoop, and independent means for positively and forcibly closing 115 said scoop acting at all times at right angles to the radius of oscillation, substantially as specified. 120

In testimony whereof I have signed my name to this specification in the presence of two subscribing witnesses. 125
